UNITED STATES PATENT OFFICE.

OTTO BALLERT, OF BERLIN, GERMANY.

TIPPING CAR.

Application filed May 9, 1927, Serial No. 190,062, and in Germany January 9, 1926.

This invention relates to a hydraulic tipping device for the loading floor or the car body of three-way tipping cars, especially freight motor-cars, and the gist of the invention resides therein that, apart from the controlling device proper, by which the source of power, viz, liquid under pressure, is controlled, a separate device is provided by which the locking, as well as the releasing of the turning joints for said floor or body is regulated.

There have been distinguished up to now, as is known, two fundamentally different types of devices for the purpose in view, viz:

15 First, that type in which, prior to starting the control-gear of the source of power, a number of the turning joints are opened mechanically and the others are closed mechanically by manual actuation, and

20 Second, that type in which the turning joints are acted on by the source of power itself, i. e. by the liquid under pressure, by the intermediary of a separate device, in such a way, that some of said joints are 25 opened automatically by said liquid.

In both cases the turning joints are opened by means of a separate device, and in the first of said cases also the closing is, under circumstances, effected by means of 30 that device.

Now, in contradistinction thereto the present invention consists therein that opening the turning joints for the loading floor or the car body is effected indirectly by this 35 floor or body itself without a separate device, and that a separate gear movement is provided by which the closing heads for the turning joints or bearings of the said floor or body are released or locked in dependency of the position of the control-gear 40 for the source of power.

The invention is illustrated diagrammatically and by way of example in the accompanying drawing in which Figure 1 is a 45 plan of the control-gear and the separate gear movement, together with the turning bearings for the loading floor or car body, the parts being shown in the position in which the floor or body can be tipped to the left; Figures 2, 3 and 4 are sections taken on the lines A—B, C—D and E—F respectively of Fig. 1, and Figure 5 is a sectional view of modified constructional detail.

55 The device consists of a shaft 1 which is provided with a grip 2 and a pinion 3, this

latter meshing with teeth 4 provided on a ledge 5 carried by one of the longitudinal girders of the frame of the car and being shiftable at or in the respective girder. A 60 similar ledge 6 is arranged practically in the same manner at or in the other longitudinal girder of the frame and is connected with the ledge 5 in a positive manner by double-armed levers 7 and 8, the thus 65 coupled members forming a so-called cinematic chain. Said levers are supported at their center portions 9 and 10 at the frame, and their slotted ends are engaged by pins 11, 12, 13 and 14 projecting from the ledges 70 5 and 6. In consequence thereof of every position of one ledge a definite position corresponds for the other ledge.

In order to obviate any dead play between the members of the cinematic chain, each of 75 the ledges 5 and 6 may comprise two parts, as shown in Fig. 2, the opposite ends of the parts being shaped as shown and connected with each other by a tension spring 58. The other ends of the ledge parts are provided 80 with holes 15 and slot-like hole extensions 16, and the diameter of said holes is such that heads 17, 18, 19 and 20 provided at the ends of rods 21, 22, 23 and 24 can enter into and through them. These rods are connected at their other ends with locking heads 85 25, 26, 27 and 28 which co-operate with the turning bearings for the loading floor in the manner hereinafter described. The rods 21—24 are supported in the axles 59, 60, 61 90 and 62 pertaining to said bearings.

In the constructional form shown in Figs. 1—4 the locking heads are rigidly connected with the outer ends of the rods 21—24, but in the modification shown in Fig. 5 they are 95 movably connected with said rods, as well as with the axles mentioned.

The said heads have oblique faces or nose-like projections 29, 30, 31 and 32 and are pressed by springs 40 (Fig. 4) against pivots 100 41. The length of the slots 16 is such that the ledges 5 and 6 can be shifted longitudinally and receive in said slots the rods 21—24 whereby these latter can be locked in certain positions due to the fact that the heads 17—20 cannot pass through said slots.

The control device carried by the bracket 33, Fig. 1, consists of a hand-lever 34, a shaft 35 to which this lever is affixed, and a crank-arm 36 also secured to said shaft. 110 The crank-arm is connected with a projection 38 which can pass through recesses 39 of

the ledge 5 only when this ledge is in certain definite positions, whereas the rod 37 is checked in all other positions of the ledge 5 whereby the control gear is locked. The attendant can, therefore, actuate this gear only after having shifted the ledge 5 into a certain definite position.

The rod 37 extends over both ledges (5 and 6) to another crank-arm 36^a connected with said rod, as well as with another hand-lever 34^a by which the rod 37 can be actuated also from the other side of the car. The rod 37 is, furthermore, provided with a pin 42 engaging a slotted arm of a bell-crank lever 43 rotatable on a bolt 44 attached to the frame of the car. The other arm of the bell-crank lever is connected with one end of a rod 45, the other end of which is coupled with the adjusting-device of the control member 46 housed in the casing of the lifting device. The rod, or control-rod, 45 extends through the liquid receptacle of the pump in such a manner that it has a certain free play and can follow freely the lateral movements of the lifting device.

As long as the control lever is not adjusted for lowering, or as long as the tipping has not proceeded so far that the locking heads 25, 26, 27 and 28 have been moved into the locking position by means of the springs 40, the position of the members for the time being cannot be changed. This might be possible, however, during the lowering of the loading floor, but means are provided for preventing any undesired re-adjustment. This means consists of recesses 56 (Fig. 1) in the ledge 6, a projection 53 adopted to engage any one of said recesses, and a spring 54, Fig. 3, holding said projection in the respective recess as long as the loading floor is not supported in any of its tipping positions. The projection 53 is inserted into a sliding bolt 55 subjected to the pressure of a spring 54 which tends to hold the bolt continually in raised position. As long as the loading floor, or the car-body respectively, rests upon all supporting points the bolt is kept continually depressed counter to the pressure of the spring 54, in consequence whereof the projection 53 does not engage any of the recesses 56. But when the loading floor or the car body is tipped, the bolt 55 will be lifted by the spring 54 and the projection 53 will enter one of the recesses 56 whereby the change-position gear is checked.

The improved device described presents the great advantage that if a spring of any of the locking heads should break and the respective locking head is, therefore, moved outwardly, any other re-adjustment of the device becomes impossible because that head then remains in its exterior position whereby the device is checked. Another advantage resulting therefrom consists therein that owing

to the tendency of the springs 48 to shift automatically the control member 46 into its lowering position the attendant is compelled to keep the control lever 34 in his hand. If this lever should become fixed in its position, the device will nevertheless be thrown out of gear in any of the final tilting positions and without any damage to the control gear, as the spring 48 will be compressed in that case.

The locking heads 25-28 operate as follows:

In the construction according to Figs. 1-4, the locking heads 25-28 are rigidly secured to the outer ends of rods 21-24. They are under the influence of springs 40 as shown in Fig. 4. These springs, at one end, abut against a shoulder of the rotatable axle, as for instance, the rotary bearing arms or axles 59-62. The other end of the springs bear against shoulders of the locking heads and exert pressure in order that the locking heads may be forced in the locking position in which they lie against the pivots 41 when the body of the car is in the lowest position and they grip the lower angular surfaces. The other inner end of the rods 21-24 terminate in rigid heads 17-20, shown in Figs. 1 and 4. At the point where the heads 17-20 are provided on the rods 21-24, ledges 5 and 6 are arranged, having perforations 15 therein which are of such a size that the heads 17-20 can enter therein when such perforations lie directly in front thereof. The perforations themselves are connected to each other by means of slots 16 which also project beyond the sides of the perforations. The length of the rods 21-24 are so arranged that their heads 17-20 project into the ledges 5 and 6 when the body is set down whereby the rods 21-24 will project through the slots 16. The slots 16 are so wide that the ledges 5 and 6 can be moved over rods 21-24. It is, therefore, possible to move the ledges 5 and 6 with the aid of the parts 1, 2 and 3 and thus secure a definite connection. Thereby the ledges are so adjusted that, as shown in Figs. 1 and 2, two rod heads 19 and 20 will not lie in front of their perforations 15 of the ledge 5 but will be at the side thereof in front of the slot, while the rod heads 17 and 18 directly opposite will be in front of their respective perforations 15 of the ledge 6. If now the control is placed in operation, that is, the hydraulic tipping arrangement is set to lift the body, then the body of the car will be raised and the pivots 41 will abut against the angular surfaces of the locking heads 25-28. Since the heads 19 and 20 of the rods 23 and 24, to which the locking heads 27 and 28 are arranged, are secured by means of the ledge 5, the locking heads 27 and 28 cannot move away but must remain in their

positions. The pivots 41 of the opposite locking heads 25 and 26 operate by means of the wedging action of the angular surfaces so that the locking heads will operate 5 outwardly against the force of the springs 40 since the heads 17 and 18 of rods 21 and 22 can project into the perforations 15 of the ledge 6. The body of the car will therefore tip to the left. In Fig. 1, the locking 10 heads are shown in open position whereby the heads 17 and 18, as illustrated, lie in the perforations 15 of the ledge 6. As soon as the pivots 41 have gripped with the angular surfaces of the locking heads 25 and 26, they 15 will set themselves again in a closing position due to the operation of the spring 40. In lowering the car, the various operations are repeated in reverse manner. The pivots 20 41 will lie against the upper angular surfaces of the locking heads 25 and 26 whereby they will move themselves outwardly against the force of the springs 40 and as soon as the pivots 41 lie in their bearing, the locking heads will move inwardly automatically 25 under the influence of the springs 40.

I claim:

1. A three-way hydraulic tipping device comprising a supporting frame having bearings and body latches; a body having combined pivot and bearing members; spring-actuated locking heads forming parts of said 30 bearings and each having two oblique faces adapted to cause automatic opening of the heads when the body is lifted or lowered, a 35 separate change-position device comprising a 35 heads when the body is lifted or lowered, a 35 separate change-position device comprising

two parallel, longitudinally movable ledges having holes therein and slots forming extensions of the holes; double-armed levers connecting said ledges with each other to 40 form a cinematic chain; and rods arranged at right angles with respect to the said ledges and having enlarged ends adapted to pass through said holes, said rods being connected with the said locking heads. 45

2. A three-way hydraulic tipping device comprising a supporting frame having bearings and body latches; a body having combined pivot and bearing members; spring-actuated locking heads forming parts of said 50 bearings and each having two oblique faces adapted to cause automatic opening of the heads when the body is lifted or lowered, a separate change-position device comprising two parallel and longitudinally movable 55 ledges and having holes therein and slots forming extensions of said holes, and one of said ledges having lateral recesses; double-armed levers connecting said ledges with each other to form a cinematic chain; rods 60 arranged at right angles with respect to the said ledges and having enlarged ends adapted to pass through said holes, said rods being connected with the said locking heads; and a spring-actuated bolt and a pin inserted 65 therein and being adapted to co-operate with any one of the recesses of one of the said ledges.

In testimony whereof I have affixed my signature.

OTTO BALLERT.
